HOUSING FOR A TORQUE TRANSMITTER OR THE LIKE

Nolan Rhodes, Shopiere, Wis., assignor to Warner Electric Brake & Clutch Company, South Beloit, Ill., a corporation of Illinois

Filed Mar. 2, 1959, Ser. No. 54,784

Term of patent 14 years

(Cl. D55—1)

FIGURE 1 is a front elevational view of a housing for a torque transmitter or the like embodying my new design.

FIG. 2 is a rear elevational view.

FIG. 3 is a right end view.

FIG. 4 is a top view.

FIG. 5 is a left end view.

FIG. 6 is a fragmentary section taken along the line 6-6 of FIG. 4.

The lines on the plate elements in FIGS. 1 and 2 represent grooving as seen in the end elevations shown in FIGS. 3 and 5.

I claim:

The design for a housing for a torque transmitter or the like, substantially as shown and described.
